METHOD OF AND MEANS FOR PERMANENTLY WAVING HAIR

Original application filed January 21, 1932, Serial No. 587,890. Divided and this application filed June 3, 1932. Serial No. 615,081.

This invention relates to that class of hair waving in which a so called permanent wave is imparted to a pre-formed tress of hair by subjecting the tress to the action of a heating chemical, such as calcium oxide, which, when moistened, will of itself generate sufficient heat to impart a permanent wave to the said tress.

This invention comprises a novel method 10 of and a novel means for controlling the rate of cooling after the development of heat generated by the self heating chemical has ceased.

I have found that the rate of cooling after 15 the development of heat has ceased can be successfully controlled by enclosing the heating chemical in a covering of heat insulating material such as asbestos or wool so that the heat will be retained for the desired length 20 of time.

An example of a hair waving pad embodying my invention is represented in the accompanying drawing in which:

Fig. 1 represents an inside plan view of the 25 pad in its unwrapped condition, the inner absorbent sheet being shown at the side of the pad and the inner wrapper sheet being shown unfolded;

Fig. 2 represents an inside plan view of the 30 pad in its unwrapped condition after the inner wrapper flap has been perforated and the inner face of the chemical containing envelope has been perforated, the inner absorbent sheet being shown interposed between the inner face of the heating chemical containing envelope and the inner wrapper flap;

Fig. 3 represents a side view of the pad wrapped around a wound tress as in use; and 40 Fig. 4 represents a longitudinal central section through the wrapped pad.

The outer wrapper of the self waving pad is denoted by 1 and is preferably made of non-absorbent material, as for instance paper. 45 The inner wrapper is denoted by 2 and is preferably made of metal foil. This inner wrapper is provided with a foldable flap 3. An envelope 4 composed of a perforable impervious material, such as metal foil, is attached to the inner face of the inner wrapper

2, which envelope contains a heating chemical, such as calcium oxide in powdered form, which chemical, when moistened, will of itself generate sufficient heat to impart a so called permanent wave to a pre-formed tress when 55 enclosed within the pad.

An inner removable sheet 5 of absorbent material, such as cotton fabric is arranged to be moistened and inserted between the flap 3 and the envelope 4 after the inner face of the envelope 4 and the folded over flap 3 of the inner wrapper have been perforated. The pressing of the flap back into place will squeeze the moisture from the wetted inner sheet into the envelope containing the heating 65 chemical.

In practice, the tress 6 is wound as usual around a mandrel 7. The tress may be moistened either before or after it is wound, by a suitable waving solution, such for instance as an ammonia solution. The inner face of the impervious envelope 4 containing the hair waving chemical is perforated as shown at 8, and the folded over flap 3 of the inner wrapper may be perforated at the same 70 time as shown at 9. The inner sheet 5 is moistened by water or by a suitable hair waving solution, such as that used for moistening the tress 6.

The pad is then wrapped around the pre-formed tress and is preferably secured in position at the scalp end of the tress by a suitable scalp protecting guard of well known or approved form, such for instance as the self locking guard 10 shown in the accompanying drawing. The outer end of the pad may be secured around the mandrel 7, as for instance by twisting the outer wrapper of the pad around the same. The exothermic action starts at once because of the application of moisture by the wetted inner sheet 5 of the pad to the self heating chemical through the perforations in the inner face of the impervious envelope. Heat is then set up within the pad in order to impart a so called permanent wave to the pre-formed tress without requiring application of heat from an outside source. It will be seen that the outside wrapper of the pad serves to confine the heat to a large extent within the pad, the steam 100

generated by the combination of the treating solution with the chemical being permitted to escape through the crimped outer end of the outer wrapper. However, to control the rate of cooling after the development of heat has ceased I provide a covering of heat insulating material as asbestos or wool, which covering is herein shown as a thick tube 11 which may be slipped over the pad as shown in Figs. 3 and 4 to completely envelop it and thereby cause the heat to be retained for the desired period of time.

This application is a division of my co-pending application filed January 21, 1932, Serial No. 587,890, entitled Method of and means for permanently waving hair.

What I claim is:

1. The method of waving hair comprising subjecting the hair to the action of a chemical which, when moistened, will generate sufficient heat to impart a permanent wave to the hair, and retaining the heat over a period of time after the development of heat has ceased.

2. The method of waving hair comprising subjecting the hair to the action of a chemical which, when moistened, will generate sufficient heat to impart a permanent wave to the hair, and controlling the rate of cooling after the development of heat has ceased by enclosing the hair within a heat insulating covering.

3. The method of waving hair comprising subjecting the hair to the action of a chemical which, when moistened, will generate sufficient heat to impart a permanent wave to the hair, and controlling the rate of cooling after the development of heat has ceased by enclosing the hair within a covering of asbestos.

4. The method of waving hair comprising subjecting the hair to the action of a chemical which, when moistened, will generate sufficient heat to impart a permanent wave to the hair, and controlling the rate of cooling after the development of heat has ceased by enclosing the hair within a covering of wool.

5. Means for waving hair including a chemical which, when moistened, will generate sufficient heat to impart a permanent wave to the hair and means for retaining the heat over a period of time after the development of heat has ceased.

6. Means for waving hair including a chemical which, when moistened, will generate sufficient heat to impart a permanent wave to the hair and a heat insulating covering for controlling the rate of cooling after the development of heat has ceased.

7. Means for waving hair including a chemical which, when moistened, will generate sufficient heat to impart a permanent wave to the hair and a heat insulating covering of asbestos for controlling the rate

of cooling after the development of heat has ceased.

8. Means for waving hair including a chemical which, when moistened, will generate sufficient heat to impart a permanent wave to the hair and a heat insulating covering of wool for controlling the rate of cooling after the development of heat has ceased.

In testimony, that I claim the foregoing as my invention, I have signed my name this 2nd day of June, 1932.

RALPH L. EVANS.
